SELECTOR ATTACHMENT FOR ADDRESSING MACHINES

Hugh J. Shinkle, Aurora, Colo., assignor to United States of America as represented by the Secretary of the Air Force

Application June 25, 1956, Serial No. 593,776

4 Claims. (Cl. 271—64)

(Granted under Title 35, U. S. Code (1952), sec. 266)

The invention described herein may be manufactured and used by or for the United States Government for governmental purposes without payment to me of any royalty thereon.

This invention relates to a selector attachment, and more particularly, to a selector attachment adapted for use with addressing machines or the like for automatically selecting cards from a number of cards ejected from such machines.

The purpose of the present invention is to provide a selector attachment to be utilized with addressing machines of any of the usual forms employed for addressing cards, such as pay cards, for sequentially selecting a card in accordance with a predetermined cycle of operation from a number of ejected cards for purposes of audit.

The selector attachment of the present invention is arranged to operate so as to select every tenth card ejected by the addressing machine and to separate the selected tenth card from the rest of the ejected cards. Also, the order of card selection is arranged to be controlled by the operator by presetting the card selector to begin operation with any ejected card between the first and tenth ejected card, for example, such as the 4th—14th—24th etc., or the 7th—17th—27th etc.

The present invention also provides a card selector attachment which may be attached to an addressing machine without any substantial modifications to the machines and at a minimum cost.

The present invention further provides a selector attachment characterized by its simplicity of construction, employing material and parts readily available, and which is easy to operate.

According to the present invention, the card selector attachment comprises a selector device adapted to be driven by an addressing machine, a card separator device operatively connected to the selector device and adapted to be attached to the addressing machine, the selector device arranged to sequentially operate the card separator in accordance with a predetermined cycle of operation so as to selectively separate a card from the rest of the cards ejected from the addressing machine.

These and other features of the present invention are described in detail below in connection with the accompanying drawings, wherein like numerals designate like parts throughout the several views, in which:

Figure 1 is a view in perspective of a selector attachment embodying the present invention and which is attached to an addressing machine;

Figure 2 is a top plan view of the card selector attachment of Figure 1;

Figure 3 is side elevation of the selector attachment of Figure 2;

Figure 4 is a front elevation of the selector attachment of Figure 2;

Figure 5 is a front elevation of a selector switch device of the selector attachment of Figure 1;

Figure 6 is a side elevation of the selector switch device of Figure 5;

2

Figure 7 is a top plan view of the selector switch device of Figure 5; and

Figure 8 is a wiring diagram for the selector attachment of Figure 1.

5 Referring now in detail to the drawings, the embodiment of the present invention illustrated therein comprises a casing 10 that may be set upon the frame 12 of an addressing machine so as to stand at an inclined position as shown in Figure 1. The casing 10 is removably 10 mounted on the frame 12 of an addressing machine by brace members 14 attached to side plates 16 of the casing 10 and adapted to be secured to the frame 12 at their lower ends. The casing 10 is further arranged to be supported at the front end thereof on the frame 12 by front 15 side plates 18 adapted to be attached to the frame 12, as by bolts or in any other suitable manner. The front side plates 18 in turn support the side plates 16 of the casing 10 by a rod 20 extending therebetween and arranged to be engaged by slots 22 in extension members 20 24 attached to the side plates 16 as shown in Figure 3. A nut 25 screwed on at each end of the rod 20 prevents disengagement thereof.

Extending transversely of the casing 10 between the side plates 16, are flanged plates 26, 28 attached thereto 25 and of which plates 26, 28, plate 26 forms a front inclined surface while plate 28 forms an upper horizontal surface in the casing 10. Over both plates 26, 28 slide four conveyor bands 30 driven by rollers 32, motor 34 and a gearing system 36 under a cover 37 as shown in 30 Figure 2. Adjustment of the conveyor bands 30 may be obtained by one of the rollers 32 being provided with bearings 38 slidably extending through slots 40 in the side plates 16 and engaged by adjustable screws 42 as shown in Figure 3. The four conveyor bands 30 are 35 further separately held by passing over an flanged plate 44 attached to the side plates 16, and which plate 44 is provided with four slots (not shown) through which pass the bands 30.

Above each conveyor band 30 there is resiliently suspended 40 a metal strip 46 provided with pins 48 and springs 50, which pins 48 guidedly extend through apertures 52 formed in rods 54 extending transversely above the casing 10 and supported on the side plates 16 as shown in Figure 4. By this arrangement, the cards carried by the 45 conveyor bands 30 slide under the metal strips 46 and are delivered to a pan or receptacle 56 mounted at the rear side of the casing 10 by a set of pins 58 engaging notches 60 formed at the ends of the side plates 16 as shown in Figure 3. A latch 62 on each plate 16 prevents 50 disengagement of each lower pin 58 and therefore of the pan 56.

The casing 10 is further provided with a card pick-up 55 device 64 consisting of a fork member 66 having a plurality of fingers 67 and mounted on the front side plates 18. The fork member 66 is, further, biased to a raised position by a spring 68. Actuation of the fork member 66 to a lower position for picking up and separating a card from the ejected cards by the addressing machine is obtained by a pair of solenoids or electromagnets 70 supported on the front side plates 18 and arranged to attract contact arms 72 on the fork member 66 during energization of the solenoids 70 by current, thereby causing the fork member 66 to rotate to the lower or extended position as shown in Figures 3 and 4.

65 Operation of the card pick-up device 64 is controlled by a selector switch device 74 mounted on a bracket 76 arranged for attachment to the frame 12 of the addressing machine. The selector device 74 comprises a casing 78 having index numerals one to ten stamped on the face 70 thereof. Inside the casing 78, a ratchet wheel 80 having a hub 82 is rotatably mounted on a stud 84 fixed to the casing 78. The ratchet wheel 80 is formed with ten teeth

86 for completing a revolution in ten steps. The teeth 86 are engaged by a stop pin 90 pivoted on a screw 92 and being urged against the teeth 86 by a spring 94 so as to permit rotation of the ratchet wheel 80 only in a clockwise direction. A nut 96 retains the screw 92 in the casing 78.

Arranged for rotation by the ratchet wheel 80, a cam 98, provided with a groove 100, is mounted on the ratchet hub 82 and fastened thereto by a set screw 102. The cam 98 is also formed with a knob 104 provided with an indicator 106 on the face thereof and in alignment with the groove 100. Rotation of the ratchet wheel 80, and, therefore, of the cam 98, is obtained by a spring loaded push rod 108 arranged to engage the ratchet teeth 86 and extending upwardly from a lever 110 pivoted at one end on supports 112 and pivotally connected at the other end to the forked end 114 of a lever 116. A spring 118 attached to the supports 112 urges the lever 110 downwardly as shown in Figure 5. The lever 116 is provided with a washer 120 welded thereto, or attached thereto in any suitable manner, which washer 120 is arranged to be engaged with the addressing machine plate drive lever (not shown) for continuous reciprocation thereby during operation of the addressing machine.

The cam 98 is further arranged to control the actuation of a circuit controller 122, which circuit controller 122 is adapted to control the electrical circuit for energizing the solenoids 70 of the pick-up device 64 mentioned above. The circuit controller 122 consists of two contacts 124, 126 on a block 128 arranged to be inserted in the upper part of the casing 78 of the selector switch 74 as shown in Figures 5 to 7. A pair of plug jacks 130 on the block 128 are connected to the contacts 124, 126. By this arrangement, the contact 124 is kept raised above the contact 126 by the cam 98 so that the circuit remains open. However, as soon as the groove 100 on the cam 98 registers with the contact 124, the contact 124 is lowered so as to engage the contact 126 and thereby to close the circuit to energize the solenoids 70 for actuating the fork member 66.

Figure 8 illustrates a simple wiring diagram of the selector attachment of the present invention. The solenoids 70 may be connected to an outlet 132 by an electric plug 134, as shown in Figure 2, while the motor 34 may be connected to an outlet 136 by a plug 138. The selector switch 74 is connected to the solenoid outlet 132 and to the main line 140. A panel switch 142 may be provided in the main line 140 for starting and stopping operation of the card selector.

In operation, the knob 104 may be first turned until the indicator 106 is set opposite any number on the face of the casing 78 in accordance with the order of card selection desired so that every tenth card beginning with the ejected card corresponding to the number on which the knob indicator 106 is set may be separated from the rest of the ejected cards. Actuation of the ratchet wheel 80 by the addressing machine through levers 108, 110 and 116 will cause the cam 98 to rotate step by step until the groove 100 reaches the circuit controller contact 124 whereby the contact 124 is lowered to make contact with the contact 126 and close the circuit. Closing the circuit, therefore, causes the solenoids 70 to energize and thereby attract the arms 72 which rotate the fork member 66 downwardly to divert a card while being ejected from the addressing machine. The conveyor bands 30 then carry the separated card to the receptacle 56. Metal strips 46, obviously, retain the card on the conveyor bands 30 until the card reaches the pan 56 in which it is dropped. In the meantime, the cam 98 has been rotated causing the groove 100 to advance so that the cam 98 again raises the contact 124 above the contact 126 thereby opening the circuit and deenergizing the solenoids 70. This action releases the fork member 66 which returns to its upper position by the action of the spring 68 and thereby allows nine pay cards to pass beneath the fork member 66 and

into a tray of the addressing machine until the next tenth card is being ejected and the cycle is again repeated.

The present invention has been described in detail above for purposes of illustration only and is not intended to be limited by this description or otherwise except as defined in the appended claims.

I claim:

1. A card selector for sequentially selecting a card from a number of cards, comprising, in combination, a selector device attached to an addressing machine frame and comprising a combined, rotatably mounted actuator and single groove cam, an electrical circuit controller having a pair of electrical contacts normally separated to circuit-open position by said cam and moved to engaged, circuit-closed position on rotation of said cam to register said cam groove therewith, a card separating device mounted on said addressing machine frame and having a rotatably mounted card pick-up device with a pair of spaced electrical contact arms, electromagnetic means mounted on said addressing machine adjacent said spaced electrical contact arms and electrically connected to said circuit controller to intermittently attract and rotate said card pick-up device to pick up a selected card on engagement between said pair of electrical contacts, and actuating means operated by the addressing machine and engaged with said actuator to continuously rotate said combined actuator and cam.
2. A card selector attachment device for an addressing machine comprising a card separating device including a main casing having a conveyor system and a card pick-up member, means attaching said card separating device to the main frame of an addressing machine, an adjustable selector device mounted on the addressing machine frame and having electrical circuit controller means intermittently operating said card pick-up member for selectively separating a card from a number of cards ejected by the addressing machine and depositing said separated card on said conveyor system, cam means sequentially controlling the operation of said circuit controller means, an actuator element continuously driving said cam means, and actuating means driven off the addressing machine driving said actuator element comprising an operating lever attached to and driven off the addressing machine, an interconnecting lever attached to and continuously reciprocated by said operating lever and a driving member affixed to said interconnecting lever and in engagement with and driving said actuator, said attaching means comprising a pair of parallel, spaced connecting members attached at one end to said main casing, a pair of parallel, spaced plate members attached at one end to the addressing machine frame and elongated interconnecting means removably attaching said plate members to said connecting members at the other ends thereof.
3. A card selector attachment comprising a frame positioned on an addressing machine, a conveyor band system mounted on said frame, a card separating device comprising a forked element having a pair of contact arms normally in raised position mounted on one end of and in alignment with said conveyor system adjacent to the addressing machine, a card selector mechanism mounted on the addressing machine, electric control means housed within said selector mechanism, operating means sequentially controlling said electric control means between circuit-open and circuit-closed position comprising lever means operatively attached to and driven by the normal operation of the addressing machine and cam means normally holding said electric control means in open circuit position and periodically moving said electric control means to closed circuit position, a pair of solenoids mounted on the addressing machine adjacent said pair of contact arms electrically interconnected with said electric control means and energized to attract and rotate said pair of contact arms and said forked element to a lowered position to separate a predetermined card from a number of cards normally ejected from the addressing machine and

deposit the selected card on the conveyor band system, and an index means incorporated in said selector mechanism for selectively controlling and setting the initial position of said cam means, said card selector attachment having means removably attaching said frame to the addressing machine comprising a pair of rear end substantially upright braces attached between the addressing machine and said frame and front end support means comprising a pair of front side members attached to the addressing machine at one end thereof and having a slotted end portion at the other end thereof, a pair of relatively elongated extension members in alignment with said front side members and having a similar slotted end portion adjacent to and in overlapping alignment with said first-named slotted end portions, and a transversely disposed rod member extending between said pairs of aligned slotted end portions in engagement therewith.

4. In a card selector attachment for an addressing machine, an addressing machine frame, a card-receiving casing having a pair of spaced, parallel raised side plates, first support means attaching the forward end of said casing to said frame, second support means removably positioning the rearward end of said casing in spaced relation over said frame, said first support means comprising a pair of relatively elongated, parallel, spaced extension members attached to said side plates and extending in overlapping relation to the forward end of said casing each incorporating a downwardly extending open end slot, a pair of parallel, spaced front side plates, each having a similar slot in alignment with the downwardly extending slots of said extension members and an elongated rod extending transversely of said side plates in fixed engagement between said pairs of aligned slots attaching said extension members to said front side plates, a first plurality of spaced, parallel flanged plates extending transversely of said casing between said side plates to form a front inclined surface, a second plurality of spaced, parallel flanged plates extending transversely of said casing between said side plates rearwardly of and spaced from said first plurality of flanged plates to form an upper, horizontal surface, a plurality of endless conveyor bands slidably received over said plurality of flanged plates, a plurality of elongated rollers rotatably positioned between said side plates to receive and drive said plurality of endless conveyor bands and power means for driving said rollers and said conveyor bands, one of said rollers having bearing mount means on each end thereof in slidable, adjustable engagement within said side plates to adjust the tension on said conveyor bands, means for ensuring separation between said conveyor bands com-

prising a separate flanged plate positioned between said side plates and incorporating a plurality of slots each receiving a separate conveyor band, a card-receiving receptacle mounted on the rear end of said casing, means 5 directing selected cards received on said conveyor bands to said receptacle comprising a resiliently suspended guide strip positioned over each conveyor band in overlapping relation thereto, a card pick-up device comprising an elongated fork member mounted on said front side plates 10 in transverse relation to said casing normally biased to a raised card-disengaged position and having a contact arm on each end thereof, means for actuating said fork member to a lower, card pick-up position comprising a pair of solenoids supported on said front side plates adjacent said contact arms and selectively energized to attract said contact arms and said fork member to a lower, card pick-up position, and means for selectively energizing said pair of solenoids comprising a card selector device mounted on the addressing machine frame, said card 15 selector device comprising a main housing indexed on the face thereof, a ratchet wheel having a predetermined number of teeth rotatably positioned within said housing, a stop pivotally mounted in said housing in normal engagement with one of said teeth to permit rotation of said ratchet wheel in one direction only, a cam having a single groove mounted within said housing for rotation with said ratchet wheel, continuous operating means for rotating said ratchet wheel and said cam together comprising a washer engaged with and continuously reciprocated by the 20 addressing machine, a bifurcated operating lever attached at one end to said washer, an interconnecting lever attached at one end to the other end of said bifurcated operating lever and pivotally supported on its other end and a spring-loaded push rod intermediately mounted on 25 one end to said interconnecting lever and engaged at its other end with the teeth of said ratchet wheel and card-selecting means for selectively actuating said solenoids to select a card from a number of cards ejected by the addressing machine comprising a pair of electrical spring 30 contacts in circuit with said solenoids and normally held in disengaged, circuit-open position by said cam and periodically movable to engaged, circuit-closed position on register of said cam groove with one of said contacts to actuate said pair of solenoids and rotate said fork member downwardly to divert a card being ejected from the 35 addressing machine.
